UNITED STATES PATENT OFFICE

JOHN H. SMITH, OF PHILADELPHIA, PENNSYLVANIA, ASSIGNOR TO WESTINGHOUSE ELECTRIC & MANUFACTURING COMPANY, A CORPORATION OF PENNSYLVANIA

CONDENSER

Application filed October 30, 1926, Serial No. 145,200. Renewed November 4, 1930.

My invention relates to condensers, more particularly of the radial-flow type, and it has for an object to provide apparatus of this character wherein air and non-condensable vapors as well as uncondensed vapors shall be cooled before entering the air off-take.

A further object of my invention is to provide a condenser which shall have the tube nest disposed to provide an air and non-condensable gas space which communicates with the air off-take, with baffle structure arranged in the space to prevent the entrance of condensate into the air off-take.

15 In my application, Serial No. 141,221, filed October 12, 1926 (Case 6433), and assigned to the Westinghouse Electric and Manufacturing Company, (which has matured into Patent No. 1,721,261) I have disclosed and claimed a form of condenser, preferably of the radial-flow type, wherein a central air and non-condensable vapor space is provided in the tube nest, this space being much larger in cross section than has heretofore been the practice. The object of this new arrangement of tubing is to improve the condenser both from the standpoints of design and of performance, for it is possible to make such a condenser 20 without increasing the size thereof very much over the existing size, while, at the same time, the radial thickness of the tube nest will be very much reduced and the tubes will be pitched and distributed in a manner which promotes the passage of 25 steam, vapors, and air therebetween. In other words, the vapor path is shortened and it is possible for steam to come into intimate contact with each tube. This makes 30 possible diminished resistance to the passage of air, steam and vapors through the nest, and, in consequence, a better vacuum. An object of the present invention is to provide air removal apparatus more particularly though not necessarily, for a condenser of this type which shall incorporate structure or which shall be so arranged that some of the tubes of the condenser may be utilized for the purpose of preliminarily 35 cooling air and non-condensable gases be-

fore they are withdrawn by the air removal means.

A further object of my invention is to provide air and non-condensable gas outlet structure for reinforcing the tube and tube plate aggregate of a surface condenser.

These and other objects are effected by my invention, as will be apparent from the following description and claims, taken in connection with the accompanying drawings, forming a part of this application, in which

Fig. 1 is a longitudinal sectional view of a condenser embodying my improvement;

Fig. 2 is an end elevation of the apparatus shown in Fig. 1;

Fig. 3 is an elevational view partly in section of a modified form of my invention;

Fig. 4 is an end elevation of the apparatus shown in Fig. 3; and

Fig. 5 is a sectional view of a further modified form.

Referring now to the drawings more in detail, in Fig. 1, I show a condenser embodying a shell 10 having an inlet 11 for steam, a hotwell 12, tube plates 13, which are preferably annular, the central portion thereof being cut out to decrease their weight. These plates support annular bands of first and second groups of tubes 14 and 15, the annular band of tubes 15 being arranged co-axially with respect to the annular band 14 and spaced slightly inwardly and radially with respect thereto. Preferably intermediate tube supports 16, supported in any suitable manner by the shell, co-operate with the tubes 14 and 15 at intermediate points of the length of the latter. With this arrangement of nested annular groups of tubes, a central air and non-condensable vapor space 17 is left, the purpose of this relatively large space being more particularly pointed out in my application aforesaid.

Water box constructions 18 and 19 are secured to the ends of the condenser shell 10, these constructions preferably being arranged to clamp or hold the annular tube plates 13 in position, the water box construction 18 being divided by partition means

18a into an inlet water box space 20 communicating with the cooling water inlet 21 and into an exit water space 22 communicating with an outlet 23, the water box structure 19 providing a space 24 for passage of water from the first-pass to the second-pass tubes.

Referring to the air and non-condensable vapor off-takes which communicate with the central air and non-condensable space 17, I show, in Fig. 1, off-take members 25 disposed adjacent to each tube plate 13, these members being tubular and connected to registering tubular members 26 having outwardly extending flanges 27 positioned against the interior sides of the tube plates 13. Aligned with and connected to the members 26, are outlet members 28 which pass through the water box structures to the exterior of the condenser and to any suitable air removal apparatus. The opposed inner ends of the off-take members 25 are connected by a tubular strut member 29 so that the connected members 25, 26 and 29, the flanges 27 being connected to the tube plates 13, constitute a strut or reinforcement structure for the tube plates, thereby making it possible to greatly reduce the number of tie or strut tubes usually employed for this purpose.

The off-take members 25 and 26 have structure cooperating therewith to assure cooling of entering air and non-condensable vapors. To this end, I show each member 25 having a substantially cylindrical wall or sleeve portion 30 which encompasses or telescopes the off-take 25, and from the flange 27 of the member 26 a similar wall of somewhat greater diameter extends inwardly from the adjacent tube plate so as to encompass the wall 30 and also the tubes 15 for a relatively short distance. The member 30 is spaced from the flange 27 so that air and non-condensable vapors passing in between the telescoping or overlapping sleeve or wall portions 30 and 31 may easily turn and enter the space within the wall or sleeve portion 30 and then pass through the openings 32 according communication with the outlet passages of the off-takes. The tubes of group 15 pass through both the tube plates 13 and the flanges 27 and the portions thereof between the wall or sleeve portions 30 and 31 function to cool the air and non-condensable gases which are leaving the condenser and which must pass about the said tube portions and thus be preliminarily cooled before they enter the offtake openings.

The condenser shown in Fig. 1 is preferably of the two-pass type, that is, the inlet chamber 20 supplies water for the first-pass and the chamber 24 furnishes a passage for water from the first-pass to the second-pass. The inner annular group of tubes 15 is preferably arranged in the second-pass; and,

in order that this may be done, I show, for example, a curved passage 33 formed by an annular member 34 enclosed by the water box structure 18, this member having an inner annular wall 35 joined to a lower, outer semi-circular wall 36 by an end portion of web 37, the walls 35 and 36 and the web portion 37 forming the passage 33, which communicates with the upper water-box space 22. Connected to the member 34 there is a surrounding member 38 joined at its outer end to the end plate of the water box structure 18, the members 34 and 38 forming a jacket space 39 surrounding the tubular member 28. By providing openings 40 and 41 in the member 38 and communicating, respectively, with the inlet water space 20 and with the outlet water space 22, cooling water may be passed through the jacket space 39 to cool the outlet member 28, thereby making it possible to further cool air and non-condensable vapors by structure embodied in the condenser structure proper.

While I have shown and described my invention as applying to a condenser in which the second-pass cooling water is circulated through the inner tube nest 15, nevertheless it will be apparent to those skilled in the art that I may readily rearrange the circulation of the cooling water so that first-pass cooling water is circulated through the inner or air and non-condensable gas cooling nest 15.

The structure shown in Figs. 1 and 2 may be changed without much modification into a single-pass condenser. Referring to Fig. 3, I show a single-pass condenser of this type, in which it will be seen that water is supplied by the inlet 43 to the inlet space 43a which communicates with the tube nests 14 and 15 at one end thereof, and that water leaves from the outlet 42 communicating with the outlet space 42a, the latter receiving water from the other ends of the tubes 14 and 15. With this modified form of construction, the outlet members 28 are freely exposed to the water within the spaces 42a and 43a so that air and non-condensable gases passing through the outlets are preliminarily cooled.

Referring to Fig. 5, the air offtake means takes the form of a longitudinal member 44 having lateral inlets 45 extending partly or wholly beneath the bottom of the core space 46 formed by the annular bank of tubes 47, as heretofore referred to. The member 44 is supported by and communicates with hollow standards 48 connected to any suitable air withdrawal means. A deflector member 49 is arranged in the core space 46 and prevents condensate from passing into the air offtake openings 45. By having outlets 45 arranged with respect to tubes of the annular nest 47 in the manner stated, it is

assured that air and non-condensable vapors shall be brought in contact with inner tubes of the annular group in passing through the openings 45, thereby assuring preliminary cooling of the air and vapors before passing out of the condenser.

From the foregoing, it will be apparent that I have provided, in connection with a condenser having tubes arranged to provide a relatively large air and non-condensable gas space, air and non-condensable gas withdrawal means, which serves to withdraw air and non-condensable gases from such space in such a way that the air and non-condensable gases are acted upon by some of the tubes in order that the air and non-condensable vapors may be preliminarily cooled. Baffle structure is provided to avoid entrance of condensate into the air offtake openings, and this structure may also serve to define an outlet passage containing cooling tubes for outgoing air and non-condensable gases. In accordance with my preferred form, the offtake means serves to reinforce the tube and tube plate aggregate.

While I have shown my invention in several forms it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a condenser of the radial-flow type, the combination of a shell having a steam inlet and a condensate outlet, tube plates connected to the shell, a tube nest consisting of tubes surrounding an air and non-condensable gas space and supported by the tube plates, an off-take having openings to receive air and non-condensable gases from said space, means arranged within the air and non-condensable space to cause air and non-condensable gases to pass about a portion of the inner tubes of said nest before entering the off-take openings, and means providing for the circulation of cooling medium through said tubes.

2. In a condenser, the combination of a shell having a steam inlet and condensate outlet means, a nest of tubes in the condenser, off-take means, baffle means extending longitudinally of the condenser for causing air and non-condensable gases to pass longitudinally of a portion of the tubes before entering the off-take means, and means providing for the circulation of cooling medium through the tubes.

3. In a condenser, the combination of a shell having steam inlet and condensate outlet means, first and second groups of tubes, the second group of tubes defining an air

and non-condensable gas space, air and non-condensable gas off-take means, spaced and overlapping wall members defining a passage for air and non-condensable gases from said space to the off-take means and said passage including the second group of tubes, and means providing for the circulation of cooling medium through the tubes.

4. In a condenser, the combination of a shell having a steam inlet and condensate outlet means, substantially annular tube plates secured to the ends of the shell, tubes disposed in annular formation and carried by the tube plates and providing a central air and non-condensable gas space of relatively large cross sectional area, air off-take means communicating with said space, and baffle means for preventing the entry of condensate into said off-take means.

5. In a condenser of the radial-flow type, the combination of a shell, substantially annular tube plates secured to the ends of the shell, tubes carried by the tube plates and disposed in annular formation to provide a central air core space, aligned with the central openings of the annular tube plates, condensate off-take structure connected to the tube plates and serving to brace the latter, and means providing for circulation of cooling water through the tubes.

6. In a condenser, the combination of a shell having a steam inlet and condensate outlet means, substantially annular tube plates secured to the ends of the shell, tubes carried by the plates and disposed in annular formation to provide for a relatively large air and non-condensable gas space, off-take members connected to the tube plates and having off-take passages adapted to communicate with said space, baffle means for causing air and non-condensable gases to pass about a portion of said tubes before entering the off-take passages, and means providing for the circulation of cooling medium through said tubes.

7. A surface condenser comprising a condensing chamber, inner and outer substantially annular banks of tubes traversing said chamber, means for directing circulating media through one of the respective banks of tubes in a plurality of passes in series and through the other of said banks of tubes in parallel with one of said plurality of passes, means providing a passage for conducting air and non-condensable gases from the central portion of said chamber, and means for subjecting said passage to successively lower temperatures in the direction of flow through said passage.

8. A surface condenser comprising a condensing chamber, substantially concentric banks of tubes traversing said chamber, means for directing circulating media through one of the respective banks of tubes in a plurality of passes in series and through

another of said banks of tubes in parallel with one of said plurality of passes, means providing a passage for conducting air and non-condensable gases from the condenser, 5 said passage means extending longitudinally of and about said another bank of tubes and through the said means for directing the circulating media.

9. A surface condenser comprising a condensing chamber, a nest of tubes traversing said chamber, an inlet and discharge water box for one end of the nest and a return water box for the other end of the nest, means providing a passage from the condensing chamber through the inlet and discharge water box for conducting air and non-condensable gases from the condenser, and means for by-passing some of the circulating water across the inlet and discharge 20 water box and about said passage for cooling the media therein.

10. A surface condenser comprising a condensing chamber, a nest of tubes traversing said chamber, the tubes of said nest being arranged in substantially annular and concentric tube banks, an inlet and discharge water box for one end of the nest arranged for directing circulating media through the outer tube tank in two passes 25 in series and through the inner tube bank in parallel with the second of said two passes, means providing a passage from the central portion of the condensing chamber along the end portions of the tubes of the inner 30 tube bank and through the inlet and discharge water box for conducting air and non-condensable gases from the condenser, and means for by-passing circulating media across the inlet and discharge water box and 35 around said passage for cooling the media therein.

11. In heat exchange apparatus, the combination of a shell structure, condensable media inlet means provided in the shell structure, a condensate outlet means provided in the shell structure, tube sheets and cooling fluid boxes disposed at longitudinal ends of the shell structure, one of said tube sheets being substantially annular in shape, cooling 45 tubes carried by the tube sheets and disposed in substantially annular formation so as to provide a longitudinally-extending core space, and a longitudinally-extending non-condensable gas off-take structure secured in the core space and joined to the 50 annular tube sheet for bracing the same.

12. The combination of heat exchange apparatus embodying a shell structure, condensable media inlet means provided in the shell structure, condensate outlet means provided in the shell structure, tube sheets and cooling fluid boxes disposed at the longitudinal ends of the shell structure, one of said tube sheets being substantially annular in shape, 60 condensing tubes carried by the tube sheets 65

and disposed in substantially annular formation so as to provide a longitudinally-extending core space, a longitudinally-extending non-condensable gas off-take structure secured in the core space and joined to the 70 annular tube sheet for bracing the same, and means disposed in the core space for cooling the non-condensable gases removed through the off-take structure.

13. In a condenser, the combination of a shell having steam inlet and condensate outlet means, tube sheets and water boxes disposed at the longitudinal ends of the shell, a nest of cooling tubes connected between the tube sheets and extending longitudinally through the shell, longitudinally-spaced tube supporting plates extending transversely of the shell and dividing the shell into a plurality of compartments disposed in free and open communication with each other, an air off-take having an outlet located near one end of the condenser and extending longitudinally through the tube supporting plates within the shell in substantially a central portion of the tube nest, and means associated with the air off-take for directing the passage of air removed thereby longitudinally over an adjacent portion of the tube nest.

In testimony whereof, I have hereunto subscribed my name this 30th day of September, 1926.

JOHN H. SMITH.
